(57) **CLAIM**

The ornamental design for a coffee pot holder, as shown and described.

DESCRIPTION

FIG. 1 is a front perspective view of a coffee pot holder showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a rear perspective view thereof; and,

FIG. 9 is front perspective view of the coffee pot holder in an opened state.

The broken lines in the drawing depict portions of the coffee pot holder that form no part of the claimed design.
